UNITED STATES PATENT OFFICE.

SANFORD A. SWENSON, OF GROTON, SOUTH DAKOTA.

PROTECTING-JACKET FOR VALVE-STEMS.

1,127,107.

Specification of Letters Patent.

Patented Feb. 2, 1915.

Application filed May 27, 1914. Serial No. 841,250.

To all whom it may concern:

Be it known that I, SANFORD A. SWENSON, citizen of the United States, residing at Groton, in the county of Brown and State 5 of South Dakota, have invented certain new and useful Improvements in Protecting-Jackets for Valve-Stems; and I do hereby declare the following to be a full, clear, and exact description of the invention, such as will enable others skilled in the art to which it appertains to make and use the same.

My invention has for its object to provide a protecting jacket for valve stems, and it is especially adapted for use in connection with exhaust valves of internal combustion engines, to prevent carbon from burning onto the valve stem, and to protect the same from heat and grease, which are 10 the cause of so much valve trouble in the breaking and sticking of the same.

To the above ends, generally stated, the invention consists of the novel devices and combinations of devices hereinafter described and defined in the claims.

Referring to the drawing, the single figure is a view, partly in vertical section and partly in elevation, showing the protecting jacket applied in working position to the 20 exhaust valve of an internal combustion engine.

The numeral 1 indicates the cylinder of an internal combustion engine surrounded by a water jacket 2. Leading from the cylinder 1 is an exhaust port or chamber 3, having formed therein a valve seat 4. Mounted on the seat 4 and normally closing the exhaust port 3, is an exhaust valve 5 of the puppet type, with its depending 25 stem working in a guide or bearing 7. This bearing is formed with upper and lower hubs 8 and 9, respectively, the former of which projects into the exhaust port 3. A volute spring 10 surrounds the hub 9, is compressed between the engine casing and a collar 11, and normally and yieldingly holds said exhaust valve closed.

The above described parts have been illustrated for the purpose of showing the improved protecting jacket applied in working position, and may be of the standard or any desired construction. Any suitable means may be employed for actuating the

exhaust valve 5, and, for the purpose of this case, it is not thought necessary to 55 illustrate the same.

On the exhaust valve 5, at the junction of the valve stem 6 therewith, is an externally threaded boss 12, which carries the protecting jacket, which is conical in form. 60 This protecting casing or jacket 13 is internally threaded, at its upper end, and screwed onto the boss 12 for common movement with the exhaust valve 5, surrounds the exposed portion of the valve stem 6 65 within the exhaust port 3, and works telescopically over the hub 8.

When the exhaust valve 5 is seated, the jacket 13 completely covers the hub 8, and when the said valve is open, said jacket 70 still covers the upper end portion of the hub 8, thus protecting the valve stem from heat and grease, and preventing carbon from burning thereon. It is, of course, understood that the improved protecting 75 jacket or casing may take various forms and be applied in different manners, depending on the construction of the engine and valve.

What I claim is:

1. The combination with an internal combustion engine having a stem-equipped valve, of a protecting jacket for the stem of said valve, spaced apart therefrom. 80

2. The combination with an internal 85 combustion engine having an exhaust port and an exhaust valve of the puppet type, of a protecting jacket for that portion of the stem of said valve exposed within said exhaust port, said jacket being spaced apart 90 from said stem.

3. The combination with an internal combustion engine having an exhaust port, an exhaust valve of the puppet type normally closing said port, and a bearing having a hub extending into said exhaust port, in which the stem of said exhaust valve works, of a protecting jacket surrounding that portion of the stem of said exhaust valve exposed within said exhaust port and 100 spaced apart therefrom and also surrounding the hub of said bearing.

4. The combination with an internal combustion engine having an exhaust port, an exhaust valve of the puppet type, and a bearing having a hub extending into said 105

exhaust port, in which the stem of said exhaust valve works, of a protecting jacket applied to said exhaust valve surrounding that portion of the stem of said exhaust valve exposed within said exhaust port, spaced apart therefrom and working telescopically over the hub of said bearing.

In testimony whereof I affix my signature in presence of two witnesses.

SANFORD A. SWENSON.
